DESIGN FOR A HAIR BRUSH

Marie E. O'Donoghue, New Rochelle, N. Y., assignor to London House Ltd., New York, N. Y., a corporation of New York

Application August 15, 1935, Serial No. 58,132

Term of patent 14 years

To all whom it may concern:

Be it known that I, Marie E. O'Donoghue, a citizen of the United States, residing at 1 Wykagyl Gardens, city of New Rochelle, county of Westchester, State of New York, have invented a new, original, and ornamental Design for a Hair Brush, of which the following is a specification, reference being had to the accompanying drawing, forming part thereof.

In the drawing:

The characteristic feature of my design resides in the provision of an arched back having an uninterrupted groove in its top side, which groove continues outwardly to the handle portion, the underside of the back being arched upwardly to connect the handle portion.

I claim:

The ornamental design for a hair brush as shown, and described.

MARIE E. O'DONOGHUE.
